UNITED STATES PATENT OFFICE

EMMETT C. HARTLEY, OF CHICAGO, ILLINOIS, ASSIGNOR TO ADDRESSOGRAPH COMPANY, OF CHICAGO, ILLINOIS, A CORPORATION OF DELAWARE

PRINTING MACHINE

Application filed April 26, 1929. Serial No. 358,191.

This invention relates to printing machines of the kind described in my co-pending application Serial No. 353,408 filed April 8, 1929, in which a plurality of printing impressions are made from a single body form and changeable address forms.

The primary object of the invention is to avoid manual handling of the address printing forms and to provide means for mechanically feeding these forms to and from printing position.

Another object of the invention is to provide a printing machine of simple, novel and compact design and construction for doing work of this class and which can be easily operated without exceptional skill and with a minimum amount of labor.

In the accompanying drawings illustrating a selected embodiment of the invention

Fig. 1 is a top plan view of the machine with the sheet holder broken away.

Fig. 2 is a sectional elevation on the line 2—2 of Fig. 1.

Fig. 3 is a transverse sectional view on the line 3—3 of Fig. 1.

Fig. 4 is a detail view.

Fig. 5 is a sectional view on the line 5—5 of Fig. 1.

Fig. 6 is a transverse sectional view on the line 6—6 of Fig. 1.

Referring to the drawings 1 designates generally the main frame of the machine which is provided with a bed 2 adapted to receive a stationary printing form and is made in any suitable shape. A stationary printing form of any suitable kind may be used but I prefer one comprising sheet metal sections having printing characters embossed thereon as shown and referred to, for example, in Patent No. 1,543,066, June 23, 1925. Ribbon spools are supported on the main frame and carry an ink ribbon 3 stretched across the printing forms on the bed as described in my co-pending application. A carriage 4 is reciprocable on a carriage frame 5 above the bed and it carries a sheet supply holder 6 and is operated by handle 7. A slide 8 is movable in transverse guides 9 in the bed and this slide is operated by a

lever 10 and a link connection 11 with the slide, Figs. 1, 6. The lever is pivoted to the frame at 12 and carries a roller 13 which operates in a grooved cam 14 on shaft 15 supported in bearings in the main frame beneath the bed. A magazine 16 is mounted on the main frame at one side of the bed to hold a supply of address printing devices 17, and another magazine 18, Fig. 2, is supported on the main frame for receiving the address printing devices after they are discharged from printing position. These used address printing devices are discharged into the magazine 18 upon a yielding support 19 which yields with the weight of the printing devices and maintains them compactly arranged in a stack. The slide 8 carries an anvil 20 provided with devices 21 for engaging the ends of a printing device 17 and retaining it on the anvil registered with a stop device 22, Fig. 5, which is pivoted at 23 on the anvil. A reciprocable frame is provided for feeding the lowermost printing device from the supply magazine 16 onto the anvil, Fig. 5, and this frame comprises two connected side bars 24 traveling on rollers 25 mounted in the main frame. The side bars have shoulders 26 to engage and push the printing device onto the anvil. A spring-pressed dog 27 is pivotally supported on the feed frame far enough beyond the shoulders 26 to permit the dog to operate to push the used printing device off of the anvil before the lowermost printing device in the magazine 16 is moved by the shoulders 26 onto the anvil. The feed frame is operated by a handle lever 28 rigidly mounted on a short shaft 29 supported in bearings in the main frame. The hub of the handle lever is provided with a segment gear 30 which meshes with a pinion 31 on the cam shaft 15 to rock said shaft. An arm 32 rigid on the cam shaft engages and operates a forked lever 33 which is pivotally connected at 34 to one end of a link 35 pivotally connected at its other end 36 with said frame. A spring 37 is fastened to the main frame and to the forked lever 33 and a yielding stop 38 is arranged on the main frame to be engaged by the forked lever. In

pushed forward initially and only a short distance to the left, Fig. 2, to move the feed frame to the right. This movement of the feed frame will eject a used printing device 5 from the anvil and will deliver the lower-most printing device from the magazine onto the anvil. The feeding movement of the feed frame is effected through the rock shaft 29, segment 30 and pinion 31, causing the 10 arm 32 to move the forked lever 33 to the right, Fig. 2, and thereby, through the link-connection 35, actuate the feed frame 24. Then the handle lever 28 is swung from its 15 forward position to the left to its rearward position to the right, Fig. 2, and during this movement the feed frame is retracted by spring 37, the slide is moved laterally by cam 14 to carry the anvil and the printing device into printing relation with the stationary form. There is sufficient lost motion 20 in the operation of the cam to permit the slide to remain at rest during the feeding and also during the retracting movement of the feed frame. After the printing device has been positioned for printing the carriage is moved forward on its printing stroke to the left, Fig. 2, and is then returned to initial position as shown in full lines in 25 Fig. 2. The handle lever is then swung forward and first the slide is moved to the left, Fig. 1, carrying the anvil into position for the operation of the feed frame to discharge the used printing device and to deliver a 30 fresh printing device onto the anvil. The machine is conveniently operated by a single operator using both hands successively, his left hand for operating the printing device feed and his right hand for operating the carriage. The stop device 22 comprises a 35 cross-bar 39, Figs. 2, 3, and side bars 40 which are arranged alongside the anvil and are pivoted at 23 thereto. A spring-pressed bolt 41 projects through the anvil and the cross-bar 39 into a recess 42 in the anvil 45 and this bolt has a shoulder 43 which engages the cross-bar. A rocker 44 is supported in the main frame, Fig. 1, and it is provided with an arm 45 which carries a stud 46 arranged to engage the lower end 50 of the bolt 41. Another arm 47, Fig. 6, on this rocker carries an adjusting screw 48 which is arranged in the path of an arm 49 on the hub of the segment 30. These devices are provided to swing the stop device 55 22 up in position to form a stop gauge for the printing device being fed forward from the magazine 16 but the parts are timed so that the stop device will not be raised until after the used printing device has been 60 pushed thereover sufficiently to permit the complete discharge of the used printing device from the anvil.

Sometimes during the operation of a machine of the character to which this invention 65 appertains, it is desirable that certain of the

printing devices introduced into the magazine be used in the printing operation, while others are, as it is termed, skipped, and to so determine whether or not a printing device is to be used in a printing operation is what is known as selection. In the present device, such an arrangement is provided, and this is done in a manner which is known as visible selection. The operation, as above described, is one which may be advantageously used in a visible selection, and by referring to Fig. 1 it may be seen that the printing device fed onto the anvil is in plain view of the operator prior to movement thereof into printing relation with the stationary printing form. In the operation, as previously described, it has been pointed out that the operating handle 28 is moved from the intermediate dotted-line position shown in Fig. 2 into the dotted-line position illustrated at the left of the intermediate position in said figure to effect the feeding operation. When the handle 28 has been moved from the intermediate position to the position at the left and back into the intermediate position, one printing device will have been ejected from the anvil, and a new printing device will have been fed thereonto. Movement of the handle 28 from the intermediate dotted-line position shown in Fig. 2 to the dotted line position illustrated at the right in said figure moves the anvil to carry the printing device into printing relationship with the stationary printing form, and movement in the opposite direction retracts the anvil back into original position. When a visible selection is desired and the printing device fed onto the anvil is to be skipped, this latter movement of the handle 28 into the dotted line position at the right in Fig. 2 is not performed, but the handle 28 is again moved into and from the dotted-line position shown at the left in Fig. 2. Thus, the operation of feeding the printing device onto the anvil may be carried out so that each printing device fed thereonto will be used in a printing operation or, if desired, the printing device may be immediately ejected therefrom without being used in a printing operation. Thus, the handle 28 and the positioning of the anvil in a visible location provide a visible selection, the advantage of which is readily apparent.

The invention provides a machine of simple and compact construction which is adapted to be easily and rapidly operated for printing and separately addressing letters. While the invention is primarily intended for use in connection with the machine of my co-pending application it is not intended to be limited to such use for it can be combined with machines of different constructions and I reserve the right to make all such changes in the form, construction and ar-

angement of parts of the invention as fall within the scope of the following claims.

I claim:

1. A printing machine comprising a main frame having a printing bed adapted to support a stationary printing form, a magazine adapted to hold a plurality of movable printing devices, means for feeding a printing device from the magazine, an anvil arranged in the path of movement of said feeding means for receiving and carrying the fed printing device into printing relation with said stationary form, and means for reciprocating said anvil laterally of the bed between the receiving and printing positions.

2. A printing machine comprising a main frame having a printing bed thereon adapted to support a stationary printing form, a magazine adapted to hold a plurality of movable printing devices, an anvil movable between an initial printing device receiving position and a supporting position wherein the printing device thereon will be disposed in printing relation with the stationary form, means for reciprocating the anvil laterally between said positions, and means for feeding a printing device from the magazine onto the anvil when the anvil is disposed in said initial position.

3. A printing machine comprising a main frame having a printing bed thereon adapted to support a stationary printing form, a magazine adapted to hold a plurality of movable printing devices, an anvil movable between an initial printing device receiving position and a supporting position wherein the printing device thereon will be disposed in printing relation with the stationary form, means for reciprocating the anvil laterally between said positions, and means for discharging a printing device from the anvil and for feeding a printing device from the magazine onto the anvil when the anvil is disposed in initial position.

4. A printing machine comprising a main frame having a printing bed thereon adapted to support a stationary printing form, a magazine adapted to hold a plurality of movable printing devices, an anvil movable between an initial printing device receiving position and a supporting position wherein the printing device thereon will be disposed in printing relation with the stationary form, means for moving the anvil laterally between said positions, means for discharging a printing device from the anvil and for feeding a printing device from the magazine onto the anvil when the same is disposed in initial position, and common manually operable means for operating the last-named means and the anvil moving means.

5. A printing machine comprising a main frame having a printing bed thereon adapted to support a stationary printing

form, a magazine arranged alongside the bed and adapted to hold a plurality of printing devices, an anvil movable between an initial printing device receiving position and a supporting position wherein the printing device thereon will be disposed in printing relation with the stationary form, means for moving the anvil laterally between said positions, means for feeding a printing device from the magazine onto the anvil, and a single manually operable means for operating said anvil moving means and said feeding means.

6. A printing machine comprising a main frame having a printing bed thereon adapted to support a stationary printing form, a magazine arranged alongside the bed and adapted to hold a plurality of printing devices, an anvil movable between an initial printing device receiving position and a supporting position wherein the printing device thereon will be disposed in printing relation with the stationary form, means for moving the anvil laterally between said positions, means for feeding a printing device from the magazine onto the anvil, a single manually operable means for operating said anvil moving means and said feeding means, and a platen carriage reciprocal over the bed and operable independently of the operating means for said anvil moving means and said feeding means.

7. A printing machine comprising a main frame having a printing bed adapted to support a stationary printing form, a magazine adapted to hold a plurality of movable printing devices, an anvil, means for feeding a printing device from the magazine onto the anvil, and means for operating said feeding means comprising a rock shaft, a handle lever for operating said rock shaft, and connections between said rock shaft and the feeding means for imparting feeding movement to said feeding means.

8. A printing machine comprising a main frame having a printing bed adapted to support a stationary printing form, a magazine adapted to hold a plurality of movable printing devices, an anvil, means for feeding a printing device from the magazine onto the anvil, and means for operating said feeding means comprising a rock shaft, a handle lever for operating said rock shaft, connections between said rock shaft and the feeding means for imparting feeding movement to said feeding means, and means for returning said feeding means to normal position.

9. A printing machine comprising a main frame having a printing bed adapted to support a stationary printing form, a magazine adapted to hold a plurality of movable printing devices, an anvil movable between an initial printing device receiving position and a supporting position wherein the printing device thereon will be disposed in printing

ing relation to the stationary form, means for feeding a printing device from the magazine to the anvil, a cam shaft, connections between the cam shaft and the feeding means for operating the feeding means, a cam on the cam shaft, means intermediate of the anvil and the cam for operating the anvil to move the same laterally between said positions and a handle lever operatively connected to said cam shaft for effecting independent operation of the feeding means and the anvil.

10. A printing machine comprising a main frame having a printing bed thereon adapted to support a stationary printing form, a magazine arranged alongside the bed and adapted to hold a plurality of movable printing devices, an anvil movable between an initial printing device receiving position and a supporting position wherein the printing device thereon will be disposed in printing relation with the stationary form, means for discharging a printing device from the anvil and for feeding a printing device from the magazine onto the anvil when the anvil is disposed in said initial position, and means for alternately operating the feeding and discharging means and a means for moving said anvil laterally between said initial and supporting positions.

11. A printing machine comprising a main frame having a printing bed adapted to support a stationary printing form, a magazine adapted to hold a plurality of movable printing devices, means for feeding a printing device from the magazine, an anvil arranged in the path of movement of said feeding means and receiving and carrying the fed printing device into printing relation with said stationary form, means for registering the printing device on the anvil, and means for reciprocating said anvil laterally of the bed between receiving and printing positions.

12. A printing machine comprising a main frame having a printing bed adapted to support a stationary printing form, a magazine adapted to hold a plurality of movable printing devices, means for feeding a printing device from the magazine, an anvil arranged in the path of movement of said feeding means and receiving and carrying the fed printing device into printing relation with said stationary form, a stop device on the anvil to limit the feeding movement of the printing device, and means for laterally reciprocating said anvil between receiving and printing positions.

13. A printing machine comprising a main frame having a printing bed adapted to support a stationary printing form, a magazine adapted to hold a plurality of movable printing devices, means for feeding a printing device from the magazine, an anvil arranged in the path of movement of said feeding means and receiving and carrying the fed

printing device into printing relation with said stationary form, a stop device, means operable from the feeding means for positioning said stop device in the path of movement of the printing device being fed onto the anvil to limit the feeding movement of said printing device, and means for moving said stop device to permit discharge of the printing device from the anvil.

14. A printing machine comprising a main frame, a magazine adapted to hold a plurality of movable printing devices, an anvil, means for discharging a printing device from the anvil, means for feeding a printing device onto the anvil, and means on the anvil operable from the feeding means and disposed in the path of movement of the printing device to limit the feeding movement of the printing device onto the anvil.

15. A printing machine comprising a main frame, a magazine adapted to hold a plurality of movable printing devices, an anvil, means for discharging a printing device from the anvil, means for feeding a printing device onto the anvil, a stop device pivotally mounted on the anvil and movable into the path of movement of the printing device to limit the feeding movement of the printing device onto the anvil and movable out of said path of movement to permit the discharge of the printing device from the anvil, and common manually operable means for actuating the feeding means and the stop device.

16. A printing machine comprising a main frame, a magazine adapted to hold a plurality of movable printing devices, an anvil, means for discharging a printing device from the anvil, means for feeding a printing device onto the anvil, a stop device, means operable from the feeding means for moving said stop device into the path of movement coincident with the feeding movement of the printing device, and means for moving the stop device out of stopping position after the printing device comes to rest on the anvil.

17. A printing machine comprising a main frame, a magazine adapted to hold a plurality of movable printing devices, an anvil, means for discharging a printing device from the anvil, means for feeding a printing device onto the anvil, a movable stop device, and means operable from said feeding means for moving the stop device into operative position to register the printing device on the anvil.

18. A printing machine comprising a main frame, a magazine adapted to hold a plurality of movable printing devices, an anvil, means for discharging a printing device from the anvil, means for feeding a printing device onto the anvil, a stop device, means cooperating with said feeding means for moving the stop device into operative position to register the printing device on the anvil,

and independent means for returning said stop device to normal inoperative position after the printing device has been registered on the anvil.

5 19. A printing machine comprising a main frame, a magazine adapted to hold a plurality of movable printing devices, an anvil, means for discharging a printing device from the anvil, means for feeding a printing device onto the anvil, a stop device, means cooperating with said feeding means for moving the stop device into operative position to register the printing device on the anvil, and yielding means tensioned when the stop device is moved into operative position and operating to return the stop device to normal inoperative position after the printing device has been registered on the anvil.

20. A printing machine comprising a main frame embodying a printing bed having a stationary printing form thereon, a magazine adapted to hold a plurality of movable printing devices, an anvil movable between an initial printing device receiving position and a supporting position wherein the printing device thereon will be disposed in printing relation with the stationary printing form, means for moving the anvil laterally between said positions, means for feeding a printing device from the magazine onto the anvil when the same is disposed in said initial position, and a handle movable in one direction for operating said anvil moving means and movable in the other direction for operating the feeding means whereby the feeding means may be operated independently of the anvil operating means to permit printing devices to be passed over the anvil without being moved into printing relation with the stationary form.

21. A printing machine comprising a main frame having a printing bed thereon adapted to support a stationary printing form, an anvil reciprocable between an initial printing device receiving position and a printing position wherein the printing device thereon will be disposed in printing relation with the stationary form, and means including a manually operable lever for reciprocating the anvil laterally between said positions.

22. In a printing machine which has a bed, supporting rails extending across the machine above said bed, a carriage movable along said rails, a platen roller mounted in said carriage, and an ink ribbon stretched over said bed, the combination of a guideway in said bed and extending from one side thereof, an anvil slideable in said guideway, and means including a manually operable lever for moving said anvil along said guideway from and to a position at the side of said bed whereat a printing device may be disposed thereon and to and from a position on said bed and below said ink ribbon whereby when said carriage is moved along said

rails said platen roller will urge a sheet toward the printing device on the anvil whereby an impression will be made on said sheet from said printing device through said ink ribbon.

23. A printing machine which has a bed, supporting rails extending across the machine above said bed, a carriage movable along said rails, a platen roller mounted in said carriage, and an ink ribbon stretched over said bed, the combination of a horizontal guideway in said bed and extending from one side thereof, an anvil slideable in said guideway, and means including a manually operable lever for reciprocating said anvil along said horizontal guideway from and to a position at the side of said bed whereat a printing device may be disposed thereon and to and from a position on said bed and below said ink ribbon whereby when said carriage is moved along said rails said platen roller will urge a sheet toward the printing device on the anvil whereby an impression will be made on said sheet from the printing device through said ink ribbon.
